UNITED STATES PATENT OFFICE.

HARRISON RICH, OF GRAND RAPIDS, MICHIGAN.

WINDOW.

No. 868,698.

Specification of Letters Patent.

Patented Oct. 22, 1907.

Application filed September 24, 1906. Serial No. 335,815.

To all whom it may concern:

Be it known that I, HARRISON RICH, a citizen of the United States of America, residing at Grand Rapids, in the county of Kent and State of Michigan, have invented certain new and useful Improvements in Windows; and I do hereby declare the following to be a full, clear, and exact description of the invention, such as will enable others skilled in the art to which it appertains to make and use the same.

- 10 My invention relates to improvements in windows, and its object is to provide improved means for readily removing and replacing the sash; to provide the device with improved means for supporting and balancing the same; to provide improved means for preventing air 15 from passing through the joints thereof; and to provide the same with various new and useful features herein-after more fully described and particularly pointed out in the claims, reference being had to the accompanying drawings, in which:
- 20 Figure 1. is a front elevation of a device embodying my invention with parts broken away to show the construction; Fig. 2. a vertical section of the same showing an elevation of one side of the case with the slides therein; Fig. 3. an enlarged detail in horizontal section on the 25 line 3—3 of Fig. 1.; Fig. 4 a detail of the casing strip; Fig. 5. a detail of one of the slides; Fig. 6. a perspective detail of a portion of a sash; Fig. 7. a detail of the key-hole plates for holding the stops; Fig. 8. an enlarged detail of the slide holding and supporting mechanism; Fig. 30 9. the same at right angles to Fig. 8.; Fig. 10 a detail of the spring catch to hold the sash in place on the slides; Fig. 11. a perspective detail of the slide holder; Fig. 12 a detail of the means for attaching the ribbon support to the slide.

35 Like numbers refer to like parts in all of the figures.

1 represents the upper sash and 2 the lower sash of the window, each provided with recesses 3 in its lower corners to receive supporting pins 4 projecting inward from the lower ends of slides 5 formed of sheet metal and 40 adapted to traverse vertical grooves in the casing opposite the respective sides of the sash and adjacent thereto and provided with inwardly projecting members 6 at the top and having openings adapted to receive upwardly projecting spring stops 7 inserted in the sash, 45 and thus to secure the sash in place between the respective slides 5. To support these slides and balance the weight thereof together with the sash supported thereby, metallic ribbons 8 or cords 8^a are attached to the slides and extend upward within the grooves for the 50 slides and thence over sash pulleys 9, and have attached thereto counterbalance weights 10. The inner edges of the slides 5 are slidably inserted in channel strips 11 formed of sheet metal folded around the inner edge of each slide and secured within the grooves of the casing. 55 The outer edge of the slides 5, to stiffen the same and form freely sliding and air-tight joints, are folded to form

channels in which are inserted the edge of weather strips 17 secured to the sash. The slides 5 thus engage and traverse the channel strips at one edge and are flexibly engaged with the weather strips 17 at the other 60 edge, whereby they readily conform to any slight variation in the space between the side of the sash and the casing, and at the same time provide a joint therebetween that will keep air from passing therethrough.

To form a finish, stops 12 may be provided which I 65 detachably hold in place by means of screws 13 inserted therein and projected through key-hole slots in plates 14 attached to the casing. These stops are short at the top so that they can be readily detached by moving them upward whereby the heads of the screws will pass 70 through the enlarged openings at the upper ends of said slots. These stops, however, may be omitted without materially affecting the operation of my device in which event the sashes are freely removed and inserted within the slides by merely detaching the spring stops 7 75 from the inwardly projecting ends 6 of the slides and moving the upper end of the sash inward clear of the said ends and lifting it off the pins 4. Opposite the upper sash and terminating near the bottom thereof, stops 12 may be also used if preferred, and these stops need 80 not be detachable. The upper sash can be removed by lowering the same below the bottom of these stops after the lower sash has been removed, but these stops also may be omitted as they are not necessary except for the matter of appearance. When the sash is removed, the 85 weights would overbalance the slides and carry the same upward. To prevent this, I provide automatic stops to hold the slides when the sash is removed. For this purpose a shoulder 15 is formed in the rear of each slide and a spring hook 19 is provided in the casing to 90 engage this shoulder and hold the slide from moving upward. When the sash is inserted in place, these hooks are automatically released by means of lugs 18 formed on the weather strip 17 and projecting therefrom sufficient to engage and move the hook out of contact with 95 the shoulder 15, thus rendering the hook inoperative when the sash is in place.

To attach the sash cord to the slide, I provide a hook 16 on each slide struck up from the slide and projecting within the channel in the casing and inserting the end 100 of the cord 8^a in a tapered or conical socket 20, forming a knot or enlargement in the end of the cord within the socket, and providing an eye 21 on the socket to engage the hook 16. If a ribbon is used, a link 22 is secured to the end of the ribbon, which serves to engage the hook 105 16 and attach the ribbon thereto.

What I claim is:

1. In a window, the combination of a casing, channel strips fixed in the casing, slides having one edge slidably in the channel strips and a groove in the other edge, a sash, 110 weather strips on the sash and engaging the grooves in the slides, and means for detachably connecting the sash and slides.

2. In a window, the combination of a casing, strips of sheet metal folded to form a channel and attached to the casing, sheet metal slides each having one edge slidable in one of the channel strips, and the other edge folded to form a groove, a sash, weather strips attached to the sash and engaging the grooves in the slides, and means for detachably connecting the sash and slides. 30
3. In a window, the combination of a casing, sheet metal strips folded to form channels and fixed in the casing, slides each having one edge slidable in one of said channels, and the other edge folded to form a groove, pins in the lower ends of said slides, a sash having recesses to receive the pins, spring stops in the sash and engaging openings in the upper ends of the slides, weather strips attached to the 15 sash and engaging the grooves in the slides, and means for counterbalancing the slides and sash. 40
4. In a window, the combination of a casing, slides vertically movable in the casing and having shoulders, spring hooks in the casing and engaging the shoulders, a sash, means for detachably connecting the sash and slides, lugs on the sash to engage the spring hooks and disengage them from the shoulders, and counterbalance cords and weights attached to the slides. 35
5. In a window, the combination of a casing, sheet metal slides in the casing and having folded edges forming

grooves, and also having shoulders in the folded edges, spring hooks in the casing and engaging the shoulders, a sash, means for detachably connecting the sash and slides, weather strips, attached to the sash and engaging the grooves in the slides, lugs on the weather strips to engage and release the hooks, and counterbalance mechanism connected to the slides. 30

6. In a window, the combination of a casing, channel strips fixed in the casing, sheet metal slides each having one edge in one of said strips and the other edge folded to form a groove, a pin in each slide, an inwardly projecting member at the top of each slide and having an opening, a cord and counterbalance weights attached to each slide, a sash having recesses to receive the pins, spring stops in the sash to engage the springs in the slide, spring hooks engaging shoulders in the slides, weather strips on the sash and inserted in the grooves of the slides, and lugs on the weather strips to engage the hooks. 40

In testimony whereof I affix my signature in presence of two witnesses.

HARRISON RICH.
